UNITED STATES PATENT OFFICE.

AUGUSTUS HAGER BRYANT, OF GLEN RIDGE, NEW JERSEY.

SAFETY-RAZOR.

1,342,370.

Specification of Letters Patent.

Patented June 1, 1920.

Application filed September 19, 1919. Serial No. 324,942.

To all whom it may concern:

Be it known that I, AUGUSTUS H. BRYANT, a citizen of the United States, and a resident of Glen Ridge, in the county of Essex and State of New Jersey, have invented a new and useful Safety-Razor, of which the following is a full, clear, and exact description.

This invention relates to safety razors and particularly to an improved holder adapted to receive blades of the type disclosed in my Patent No. 1,309,456, issued July 8, 1919, and has for an object to provide an improved construction wherein the blade may be placed in position and removed without danger of injuring the edge thereof.

Another object of the invention is to provide a holder for a thin blade which will expose the entire length of the cutting edge of the blade and which will hold said cutting edge firmly along a predetermined line in respect to the holder.

A still further object more specifically is the provision of a holder or head for a safety razor blade which is formed comparatively thin and compact and with all of the resilient or spring members formed as integral parts of the head.

In the accompanying drawing:—

Fig. 1 is a front elevation of the safety razor with the blade removed and the parts shown in an open position.

Fig. 2 is a top plan view of the construction shown in Fig. 1.

Fig. 3 is a section through Fig. 1 on line 3—3.

Fig. 4 is a view similar to Fig. 3, but showing the parts in a closed position.

Fig. 5 is a fragmentary perspective view of the top and bottom plates of the head illustrating the arrangement of springs and associate parts.

Fig. 6 is a view similar to Fig. 5, but showing a slightly modified construction.

Fig. 7 is a sectional view through Fig. 6 on line 7—7.

Fig. 8 is a sectional view through Fig. 6 on line 8—8.

Fig. 9 is a view similar to Fig. 7 showing the parts closed and the blade in place.

Fig. 10 is a front and edge view of the blade capable of use with the holders shown in Figs. 1 and 6.

In the construction of safety razors here-tofore heads have been formed to hold the blade in place for producing a cutting oper-

ation, and various means have been utilized for correctly positioning the blade in the holder. In addition springs have been connected with certain parts of the head for preventing any loose motion of the blade, but these springs have not fully and satisfactorily accomplished their object unless adjusted very carefully and accurately. This adjustment is expensive and often times is disturbed before the razor comes into use. In addition enlargements or projections have been provided for receiving a handle and springs for clamping the upper part of the holder against the blade.

In the present invention it is aimed to overcome these various objections and also other objections and at the same time present a very thin or flat construction of head which is neat and strong. In embodying the invention two variations have been illustrated in the drawing, though it is understood that other slight variations may be made without departing from the spirit of the invention.

Referring to the accompanying drawing by numerals, 1 indicates a handle which may be of any desired construction and which is screwed or riveted into a depressed portion 2 in the bottom plate 3 of the head. The plate 3 is substantially flat and is provided with guard fingers 4 near one edge of substantially the usual form, but preferably connected by a connecting bar section 5. Adjacent the opposite edge of plate 3 are a pair of hinge knuckles 6 adjacent each end of the central projection 7 arranged therebetween, said projection being slightly bent for receiving the bent over spring extension 8 formed as an integral part of the top 9. The plate 3 is in addition provided with up-standing stops 10 and 11 having substantially square shoulders 12 and 13 for receiving the projecting ends of the blade 14 shown in Fig. 10, said blade being formed according to my patent above referred to.

The top plate 9 is preferably slightly curved as illustrated in Fig. 3 and is provided with overlapping flanges 15 and 16 which overlap the stops 10 and 11, and with ears 17 and 18 which overlap the end knuckles 6 so as to produce a finished appearance and cover the pintles 19, these pintles, two in number, being screwed into the respective end knuckles as illustrated in Fig. 1. Arranged on the back edge of the top plate 9 are hinge knuckles 20 and 21

adapted to fit between the respective knuckles 6 of plate 3 so as to accommodate the respective pintles 19. On each side of the main spring 8 and spaced slightly therefrom, are spring arms 22 and 23 arc-shaped near their base, but gradually straightening out toward the outer end so that when the parts are moved from the position shown in Fig. 3 to that shown in Fig. 4 the outer 10 ends will engage the back of the blade 14 and gradually press the same until the projecting ends of the blade engage permanently the shoulders 12 and 13. In case there should be any further movement of the top plate 9 15 the springs 22 and 23 will merely be compressed without producing any additional movement of the blade, and consequently the blade will be held firmly in position with the cutting edge thereof approximately 20 above the center of the series of up-loops 24 of the guard 4. By positioning the blade in this manner and holding the same firmly in place the blade is the first thing which strikes the face when the device is in use 25 and there will be a cutting or shaving action for the full length of the blade, as there are no obstructions in the way.

The arrangement of the spring arms 22 and 23 and the main spring 8, as illustrated 30 in Fig. 5, prevents any accidental dislocation or molestation of the adjustment, so that the top plate 9 snaps firmly into position against the blade when closed, and the spring arms also press at spaced points against the back 35 of the blade. The spring arms are usually made slightly longer than necessary to force the projecting ends of the blade against the shoulders 12 and 13, but this extra length is merely pressed or bowed back and acts in 40 the double capacity of holding the blade more firmly in place and as an insurance against not contacting with the back of the blade.

In manufacturing and setting up the parts 45 the plates 3 and 9 are stamped out and formed to appear as shown in Fig. 5, except that the ears 17 and 18 are not yet turned over. The pintles or pins 19 are screwed into place after the knuckles 20 and 21 and 50 the various knuckles 6 have been interlocked. The ears 17 and 18 are then bent over and polished if desired. This completes the assembling of the head. When the device is to be used the end flanges 15 and 16 are 55 grasped and the top plate 9 swung to an open position as shown for instance in Fig. 3, the blade 14 is then placed in position flatwise against the plate 3, or if desired it may be placed loosely and flatwise against 60 the top plate 9 after which the top plate is hinged over and the blade will fall automatically into place. During the closing action of the top plate 9 the spring 8 will pass what may be termed dead center and will urge the 65 plate to a closed position as shown in Fig. 4.

As the top plate moves to this closed position the spring arms 22 and 23 will engage the back of blade 14 and move the blade until it presses tightly against the shoulders 12 and 13. It will be noted that the blade 14 70 is not slid flatwise over the plate 3, but is laid flatwise against the same, the movement being in a direction normal to the face of said plate whereby the cutting edge will not touch any part of the head. 75

In Figs. 6 to 9 inclusive will be seen another or second form of the invention in which the barrels 6' are bent upwardly instead of downwardly as shown in Fig. 5, while a central extension 25 is provided 80 somewhat similar to extension 7, but co-acts with a spring extension 26 which is at an obtuse angle from the body part of the back 9', which back is preferably straight instead of arc-shaped. The front edge of 85 the back plate 9' is slightly curved at 27 so as to press against the blade 14 near the front edge. In this form of the invention, as well as the form shown in Fig. 5, the spring for closing the top plate 9' is made 90 from part of the head instead of an extra spring, but instead of using the extension from the plate 9' as the sole, or almost the sole spring action both the projections 25 and 26 act as spring members, which will, 95 in a certain sense, lock the plate 9' open and lock the same closed. In addition, instead of forming the spring arms 21 and 22 with rather long projections, spring or resilient eccentrics 28 and 29 are provided which 100 gradually force over the blade 14 until it presses tight against the shoulders 12 and 13. In case the arc of the eccentric cam is too large the resilient feature will take care of the extra size and consequently the cam 105 will be compressed or brought under tension, though it will not be sufficiently strong to in any way overcome the action of the main spring 26. If a true solid eccentric was provided the blade would be pushed 110 over against the shoulders 12 and 13, but the eccentric would have to be absolutely true and also the back of the blade would have to be absolutely true to secure good results. However, by providing a resilient 115 eccentric cam any unusual size or inaccuracies will be taken up by the resilient action of the spring features of the eccentrics. 120

What I claim is:

1. A safety razor head comprising a bottom plate adapted to receive a blade having a reinforced back, said plate being formed with a pair of side stops against which the reinforced back of the blade contacts, a top plate pivotally connected with the bottom plate, a spring for holding closed the top plate, and a pair of spaced coiled spring arms integral with the top plate positioned to engage and press said blade against said stops. 125

2. A safety razor head formed with a bottom plate having a pair of upstanding stops for receiving a blade having projecting shoulders at the ends adjacent the back, said shoulders being adapted to engage said stops while the cutting edge is positioned adjacent the front edge of the bottom plate, a top plate hinged to the bottom plate, a spring integral with the top plate for holding the top plate closed and a plurality of coiled springs for pressing the projections on said blade against said stops. 5
3. A safety razor head comprising a bottom plate having a pair of stops for receiving shoulders of a blade, a top plate hinged to the bottom plate for clamping the blade flatwise against the bottom plate, and a plurality of resilient eccentrics actuated by the top plate as it is closed for pressing against the rear edge of the razor blade and causing the shoulders thereof to engage said stops. 10
4. A safety razor head comprising a substantially flat bottom plate having guarding fingers and a pair of stops for receiving a razor blade having shoulders adjacent the ends, a substantially flat top plate hinged to the bottom plate, said top plate having a projecting spring member formed integral therewith, and a resilient eccentric arranged on each side of the spring and actuated by the top plate, said spring acting to press the top plate against said blade when closed and to hold the top plate open when the parts are in an open position, said eccentric 25 acting on the rear edge of the blade for pressing the shoulders against said stops during the closing action of said top plate. 30
5. A safety razor head comprising a bottom plate having a pair of stops and a central spring projection, said stops being adapted to receive the shoulders of a blade, a top plate hinged to said bottom plate formed with a spring projection integral therewith co-acting with the projection on the bottom plate, and a plurality of spaced eccentric spring members resiliently pressing against the rear edge of said blade during the closing movement of the top and after the top has been closed for holding 45 said shoulders against said stops. 50
6. A safety razor head comprising a bottom plate adapted to receive a blade, said bottom plate being formed with stops to limit the movement of the blade in one direction, a top plate, means for holding the 55 top plate closed, and a pair of coiled spaced spring arms integral with the top plate positioned to engage and press said blade against said stops. 60
7. A safety razor head comprising a bottom plate adapted to receive a blade, said bottom plate being formed with stops to limit the movement of the blade in one direction, a top plate, means for holding the top plate closed, and a pair of spaced resilient eccentric cams operated by the top plate and positioned to engage and press said blade against said stops. 65
8. A safety razor head comprising a bottom plate adapted to receive a blade, said bottom plate being formed with stops to limit the movement of the blade in one direction, a top plate, means for holding the top plate closed, and a pair of spaced resilient cams integral with the top plate and positioned to engage and press said blade against said stops. 70
9. A safety razor head comprising a bottom plate having a pair of stops adjacent each end for receiving the shoulders or projections of a shouldered blade, a top plate hinged to the bottom plate, a spring integral with the top plate and engaging the bottom plate in such a manner as to cause the top plate to snap into a closed position 75 when forced toward the bottom plate, and coiled means carried by the top plate for pressing the blade so that the shoulders thereof will engage said stops. 80
10. A safety razor head formed with a bottom plate having a pair of upstanding stops for receiving a blade having projecting shoulders at the ends, said shoulders being adapted to engage said stops while the cutting edge is positioned adjacent the front edge of the bottom plate, a top plate hinged to the bottom plate, and a plurality of springs integral with the top plate for pressing against said blade for causing said shoulders to firmly engage said stops. 95
11. A safety razor head comprising a bottom plate having a pair of stops, a top plate, means for holding said top plate closed against said bottom plate, and a plurality of resilient eccentric cams integral with the top plate and actuated thereby for pressing the blade and causing the blade to engage said stops. 105

AUGUSTUS HAGER BRYANT.
